UNITED STATES PATENT OFFICE.

HENRY E. SMYSER, OF PHILADELPHIA, PENNSYLVANIA.

PACKAGE MAKING AND FILLING MACHINE.

SPECIFICATION forming part of Letters Patent No. 449,275, dated March 31, 1891.

Application filed September 14, 1887. Serial No. 249,709. (No model.)

To all whom it may concern:

Be it known that I, HENRY E. SMYSER, a citizen of the United States, residing in the city and county of Philadelphia, State of Pennsylvania, have invented a new and useful Improvement in Package Making and Filling Machines, which improvement is fully set forth in the following specification and accompanying drawings.

10 My invention consists of novel improvements in a machine for making packages and filling the same, the nature of which will be best understood as described in connection with the drawings, and the features which I 15 desire to protect by Letters Patent are hereinafter set forth in the claims.

Figure 1 represents a partial top view and partial horizontal section of a package making and filling machine. Fig. 2 represents a 20 vertical section of a portion on line $x-x$, Fig. 1. Fig. 3 represents a vertical section of a portion on line $y-y$, Fig. 1. Fig. 4 represents a view in elevation of a portion of the device, showing the carriers, their actuating and 25 locking devices, with adjacent parts. Fig. 5 represents an elevation at right angles to that shown in Fig. 4 and of substantially the same parts. Fig. 6 represents a view showing a portion of the matrix with operating mechanism. Fig. 7 represents an end view of a 30 portion of a matrix. Fig. 8 represents a view of the part shown in Fig. 6 in different positions. Fig. 9 represents a horizontal sectional view of the matrix and mold with the folding-blades which coact therewith. Fig. 10 represents a view showing the parts shown 35 in Fig. 9 in different positions. Fig. 11 represents a view of the sheet-table with its operating mechanism. Fig. 12 is a horizontal sectional view of the mechanism for operating the pair of folding-blades which coact with the matrix and former. Fig. 13 represents a 40 vertical sectional view through one of the folding-blades and the guide in which it moves. Fig. 14 represents a side view of the triangular folding-blades with their operating mechanism, and of the other folding devices which form the bottom of the bag. Fig. 45 45 represents a horizontal sectional view of the parts shown in Fig. 14, excepting the rear folding-blade. Figs. 16 and 18 represent views of the racks and gears used in connection with

folding-blades. Fig. 17 represents a side view of the pasting-fingers and glue-pot used in forming the bag-bottom. Fig. 19 represents a view of the mold, the plunger at the bottom thereof, and the folding-blades extending outwardly. Fig. 20 represents a view showing the plunger moving through the table below the mold and one of the rotating pockets. Fig. 21 represents a view showing the parts shown in Figs. 19 and 20, but in different positions, the plunger being raised out of the pocket. Fig. 22 represents a side elevation showing the mechanism which actuates the plunger or plate 90. Fig. 23 represents a horizontal sectional view of the guides and reciprocating plate to which the plunger-rod is attached. Fig. 24 represents a view of the mechanism which actuates plunger or plate 90. Fig. 25 represents a top view of the locking-plate of the sheet-carrier shaft. Fig. 26 represents a view of the notched disk employed in rotating the carrier-shaft and the reciprocating pin which engages it. Fig. 27 represents a view of the operating mechanism of the reciprocating pin shown in Fig. 26. Fig. 28 represents a side elevation of one of the bottom folding-blades with its operative mechanism. Fig. 29 is a perspective view of one of the same blades. Fig. 30 is a side view of a portion of the device, showing the weighing mechanism and connecting parts. Fig. 31 represents a horizontal view of a portion of the weighing mechanism, showing the overflow-box with rotary false bottom. Fig. 32 represents a vertical sectional view of the overflow-box shown in Fig. 31. Fig. 33 represents a sectional view of the same, on an enlarged scale, showing the openings in the true and false bottoms. Fig. 34 represents a vertical section of the weighing mechanism, showing interior of overflow-box and mechanism for adjusting the diaphragm. Fig. 34 represents a view of the operating mechanism for the gate of the chutes leading to the scale-pans. Fig. 35 represents a sectional view of the table and a pocket, showing also the device for shaking the filled package. Fig. 36 represents a horizontal view of the mechanism for closing the top of the bag. Fig. 37 represents a side elevation, partly in section, of the same mechanism. Fig. 38 represents a bottom view of folding-blades and

sliding rack used in closing the package. Fig. 39 represents a vertical sectional view of a portion of the table and a rotary rim holding a series of pockets with a plunger for removing a bag from a pocket of the table and other devices connected therewith. Fig. 40 represents a plan view of the slide and operative mechanism for placing the bag on the endless belt or apron. Fig. 50 is an irregular transverse section of the device in elevation. Fig. 41 represents a view showing the slide in line with the belt. Fig. 42 represents a view showing the means for compressing the bag while in the pocket of the table. Fig. 43 represents a perspective view of the mold employed for forming the bag. Fig. 44 represents a plan view of a sectional pocket with a portion of the mechanism for compressing the contents of the pocket. Fig. 45 represents a bottom view of a section of the rotating rim on the table with operating mechanism. Fig. 46 represents a view of the true bottom of the weighing overflow-box, showing the openings in the same. Fig. 47 represents a side view of the device. Fig. 48 represents a sectional view on line $z z$, Fig. 47. Fig. 49 represents a sectional view on line $z' z'$, Fig. 47. Similar letters and numerals of reference indicate corresponding parts in the several figures.

Referring to the drawings, A designates the frame of the machine, and B designates a counter-shaft horizontally thereon and carrying a cam I, with which engages a lever 2, which is supported on the frame A and connected by a rod 2^x with a lever 2^{xx} , provided with a pawl 3, which latter meshes with a ratchet 4 on the vertical shaft 5, to which the pasting-table or rotary disk C is secured.

Sustained above the table C is a paste-distributer D, which consists of a plate 6, arranged vertically in the guides 7, which are supported on the frame A and shaft 5 x . (See Figs. 1 and 2.) To the horizontal upper limb of the guides 7 are fitted screws 8, which pass through the upper limb of the plate 6, and by means of nuts 7^x and springs 7^{xx} said plate may be vertically adjusted so as to regulate the quantity of paste distributed on the table, it being noticed that the paste is primarily placed on the table, and as the latter is rotated by the ratchet 4, pawl 3, rod 2^x , levers 2 and 2^{xx} , cam I, and shaft B the required quantity of paste is carried under the bottom of plate 6, and thereby nicely and uniformly spread upon the table C. Over said table pass paper pasters and carriers E, which consist of horizontal plates or frames 9, which are secured by arms to the vertical shaft 10, the latter being mounted on the frame A.

Adjacent to the table C is a table 11 for holding a pile or number of sheets of paper, and adjacent to said table 11 is a table 12. The table 11 has upwardly-extending fingers 50, between which a package of blanks is held, and it is supported upon a spring, so as to move downwardly under the pressure of a paster

and carrier-arm E and return to its original position as such pressure is removed. As shown, a supporting-rod 51 passes down through bearings in a plate 54 and in a portion 56^x of the frame, a spring 57 being secured between said frame and a collar 58 on the rod. The plate 54 is adjustable vertically, a supporting-rod passing through a bearing 55, as shown, and a set-screw 56 holding it at the desired height.

52 52 are guide-arms secured to table 11 and passing through bearings in plate 54.

Supported on an arm attached to frame A 80 is a matrix E^x , which is of the form of a three-sided tube, open at both ends and one side, and having preferably flanged tables or wings 14, which are rigidly connected with the walls of the matrix at the open side thereof. (See Figs. 1, 5, 9, and 10.)

F designates a mold or form, which is secured to the frame of the machine and so located that it may be embraced by the matrix.

The matrix E^x is arranged so that it will lie 9c in a horizontal position, with its wings 14 parallel to the tables C, 11, and 12 to receive a sheet of paper. It is then turned up so as to assume a substantially vertical position parallel to the former F and then moved toward 95 said former, so as to inclose it, thus folding the paper into a U form around the mold F, and after the paper has been further acted upon to form it into a tube the matrix is returned to its horizontal position to receive another 100 sheet. These motions in the plan shown in the drawings are accomplished by the devices below described. The matrix, I may here note, is made adjustable in size by means of a plate 24 xx and adjusting-screws 24 xxx , and the 105 former or mold F is given any desired size by being made in two parts and provided with adjusting-screws 60. The adjustable bottom is not essential, as its matrix will operate, even if its bottom never comes against the former. 110 The outer face of the mold is recessed or grooved, as shown at 61, Figs. 43, 9, and 10, so that the pasted portion of the blank will not come in contact with the mold as the tube is removed from it. I will also here note that, 115 as shown, the matrix is longer than the mold, and to give passage to the side flaps, formed in the blank in forming a bottom upon it, triangular openings 59 are formed through the sides of the matrix. These are only necessary when the elongated matrix is used. Where the matrix does not extend below the mold, they could not, of course, exist. Secured to the side of the matrix is a crank 15, to which is pivoted a pitman 16, the lower end of the 120 latter being pivoted to a lever 17, which is engaged by a cam 18, whose shaft 19 is mounted on the frame A. (See Figs. 5 and 6.) It will be seen that when the cam rotates motion is imparted to the lever 17, pitman 16, and crank 15, whereby the matrix is turned from the horizontal position shown in Figs. 4, 5, and 6 to the vertical position shown in Figs. 8, 9, and 10, said matrix after accomplishing its purpose

125

again returning to a horizontal position, as will be hereinafter more fully explained.

When the matrix is in vertical position, it is advanced to and from the mold F by means of an arm 20, which is pivoted to the frame A, and has secured to it above its axis an arm 21, carrying a roller 22, which engages with a cam 23 on the shaft 19, it being seen that the rotation of the cam 23 operates the arms 21 and 20, so as to move the matrix forward and backward, the positions of the matrix in relation to the mold being shown in Figs. 9 and 10. The sides of the matrix may be slotted, as at 24, to receive the folding-blades G, (see Figs. 10, 12, and 13,) said blades, which fold the ends of the blank around the back of the mold, being connected with arms 25, to which motions are imparted by means of links 26 and levers 27, the latter having their axis on the frame A and engaged by cams 28, whose shafts 29 are mounted on said frame A. Occupying a portion of the slots are rollers 24* (see Fig. 10) to prevent injury to the paper when the matrix passes over the mold. The slots 24 are not essential, as the folders may pass in front of the matrix.

The paper pasters and carriers E E are arranged to rotate and move vertically intermittently. Thus one of them being above the paste-table C is moved down into contact therewith and rising carries with it paste from said table. It is then revolved till it comes over the paper-table 11, then again moved down till it presses on the top sheet, and rising carries said sheet with it, the paper sticking to the pasted surface. It is again revolved till it comes over table 12, which is opposite the paste-table C, and again moves down against said table, thus, as it were, taking a fresh hold on the sheet of paper, and also where two or more carriers E are used balancing the pressure on the carrier-frame as a whole. Moving up again the carrier is revolved to a position over the horizontally-lying matrix E*, upon which or the wings of which it presses the sheet on its next vertical downward movement. While the carrier is pressed down on the matrix a paper-holding device H, having dependent fingers (see Fig. 5) arranged to pass through spaces in and about the carrier E, is pressed down on the paper and holds it down while the carrier rises preparatory to its next rotative movement. The said holder next rises, leaving the blank on the wings or table of the matrix.

To give the carrier-arms E the described motions, they should be secured to a support arranged to rotate and move vertically, and actuating mechanism must be provided to give the said motions at proper times. As shown, the carriers are secured to a shaft 10, which is journaled in the frame, and to which a cam 38, Figs. 4 and 5, gives vertical movement through lever 39, which, as shown, engages the top of the shaft by rolls 41 41, which enter between collars 42 42, secured thereon. A spring may be arranged, as shown, at the

bottom of the shaft, to sustain its weight and decrease the strain on the cam. The intermittent rotation of the carriers is accomplished by a reciprocating lever 46, one end of which is secured to a sleeve 46*, which sleeve is suspended from the frame and concentric with the shaft 10, which it surrounds. This sleeve and lever are capable of an oscillatory movement, but are vertically stationary. Their movement is derived from a cam 49, acting through lever 48 and connecting-rod 47. Depending from lever 46 is a lug or finger 45, and secured to the carrier-support (shaft 10) is a plate 43, having notches or perforations 44 formed in it, so as to come in turn beneath the finger 45, and equal in number to the intermittent rotative movements required. The mechanism is arranged so that after each downward movement of the carriers the following upward movement will cause one of the slots 44 to engage the finger 45. The lever 46 then makes a partial revolution, turning the carriers to their next position, and they are then again depressed, the lever moving back to its original position ready to engage the next notch as the carriers again rise. In order to prevent rotary movement of the carriers during their vertical movements, I provide a holding device arranged to lock the carriers from rotation before they are released from engagement with the reciprocating finger 45 and keep them locked again until engaged by said finger, as shown. This locking device consists of a plate 63, having perforations in it corresponding to those in plate 43, said plate 63 being secured to the frame and the shaft 10 passing through it, and to act with said plate I provide pins 64, secured to shaft 10, as shown at 65. It will be seen that as the carriers move down the pins 64 will enter the perforations in plate 63 and lock the shaft against rotation as the disk 43 is moving down and before the slot 44 has cleared the pin 45. So, also, the pins 64 will retain their engagement until the pin 45 again engages a slot in disk 43. The reciprocating pin 45 may be guided in any convenient way as well as by the lever 46, and of course the locking-pins could be attached to the frame and the plate to the shaft, instead of being attached as shown. These are mere obvious mechanical expedients.

The holder H, used to detach the blank from the holder, is attached to an arm 30, guided on shaft 10, and by a connecting-rod 32, moving in guide 33, said rod receiving its motion from cam 36 through lever 35 and link 34.

The sheet of paper is formed into a tube by the matrix over the mold, as has been stated, and the advancing of the folding-blades G, (see Fig. 10,) after which the bottom of the tube requires closing. This is accomplished as follows:

Referring to Fig. 14, 66 represents a table, on which is supported a slide or tucking-blade 67, which is moved to and fro by means of a

link 68 and lever 69, the latter being engaged by a cam 70 on the shaft 71, the slide being so located as to move under the matrix, so as to fold down on the mold one side of the paper tube, this operation being shown as commenced in Fig. 14. The angular folders 72 now advance within the partly-folded bottom of the tube and are rotated outward, so as to form the sides of the tube out; and, as shown, 10 through the openings 59, said folders 72, which rotate in reverse directions, being of the form of flat blades and connected with toothed shafts 73, which mesh with double rack-bars 74, which extend at a right angle to the shafts 15 73, and are operated by a link 75, a lever 76, and cam 77 and cam-shaft 77^x, (see Figs. 14, 15, 16, and 18,) said lever and cam being properly mounted on the frame of the machine, it being noted that the toothed shafts 73 are journaled 20 on a slide 78, which is parallel with the slide 67 and operated by a link 79, a lever 80, and a cam 70^x, similar to the cam 70 on the shaft 71. The folding-blade 85 then moves in, folding down the back flap of the bottom upon 25 the front flap, the sides of the blank being folded into triangular form over the folders 72. Blade 85 is actuated (see Figs. 8, 14, 28, and 29) by an arm 86, pivoted to arm 20 below its axis and operated by a link 87, lever 88, and cam 89 on shaft 19. The triangular side flaps are then pasted, as shown, by the fingers 81, (see Figs. 17 and 19,) which fingers dip into cups 82, (see Figs. 4 and 17,) said cups being secured to rod 20, so as to move therewith, the fingers 81 being pivoted to arm 20 and raised and lowered by arm 82^x, lever 83, and cam 84. The folders 72 then revolve inwardly, turning the pasted triangular flaps down upon the front and back laps of the bag-bottom, the blade 85 being drawn back just before the flaps are completely folded down and the plunger or presser-plate 96 rising and clamping the bottom against the plunger 90. The bag at this stage is directly over the 45 pocket 95 of a table J, which will be herein-after more fully described.

The plunger 90 is located within or at the bottom of the mold F, (see Figs. 14, 19, 21, and 22,) and rises and falls by means of a 50 sliding bar 91, passing through the mold, and which is fitted in guides 92 on the frame A and connected with a lever 93, to which motion is imparted by a cam 94 on shaft 71, said lever and the cam-shaft being mounted on the 55 frame A.

The plunger 96 is located, as shown, below the pocket 95, and is adapted to rise therein and meet the bottom of the bag as formed and press upwardly against the same, the 60 bottom of the bag thus being subjected to the pressing action of the two plungers in opposite directions. After the pressing action both plungers are lowered and the bottom of the bag is at or about the level of the table J. The plunger 90 now rises clear of the 65 pocket.

The plunger 96 is raised and lowered by a

sliding bar 97, link 98, lever 99, and cam 100, the latter mounted on the shaft 100^x, said lever and the cam-shaft being mounted on 7c the frame A.

The pocket 95 is one of a series, the others of which are designated by the same numeral, together with a cross or star, said pockets being secured together and to a supporting device, which sustains them in place above the table J and permits of an intermittent rotation of the series. As shown in the drawings, the pockets 95 are secured to a rotatable annulus or ring J', having projections or 80 teeth 102, with which engages a dog 103, to which is pivoted a rod 104, having shoulders 105 at the ends thereof, said rod being embraced by the arm 20, which has an opening to receive the rod, (see Figs. 6 and 45,) it being noticed that the arm 20 in its operation moves the rod 104 in opposite directions, so as to withdraw and return the dog 103 from and to the stops 102, whereby the rim is free to be rotated, and when rotated will 90 be stopped at the proper time and prevented from rotations while other operations are being accomplished. The rim J' has a serrated periphery 106, the teeth thereof being engaged by a pawl 107, which is hung on a lever 108, mounted on the axis 101 of the tube, said lever being operated by an arm 109, lever 110, and cam 111 on one of the shafts 29, said lever being mounted on the frame A. The pocket 95 and other pockets 95^x are secured to the rim J', so as to rotate therewith, (see Figs. 1, 39, and 42,) the several pockets being open from top to bottom.

To follow the operation of the machine, the bag, as has been stated, is in the pocket 95, 105 and is carried along by the rim J' until it arrives under the filling-chute J^o, (see Figs. 1 and 30,) the top of the bag being shown in Fig. 30 as projecting above the pocket 95, so that said top may be subsequently folded 110 down or closed when the bag is filled.

K designates a hopper which receives the supply of material to be packed. Communicating with the hopper is a conveyer L, whose endless apron carries the material from the 115 hopper K to the top hopper 111. Located below the latter hopper is a box 113, having within the same a vertical plate 114, which has swiveled to its arm 115 a nut 116, fitted on a screw 116^x on a slide 116^{xx}, connected 120 with said box, whereby said plate may be moved laterally, and thus adjusted so as to increase or decrease the capacity of said box 113. (See Figs. 30, 31, and 34.) The box, and consequently the slide, has motions imparted 125 to it in order to carry the contents of the box from the base 117, on which said box rests as a bottom, over the opening 118 of a chute 119, the latter having forks or branches at its bottom, so that there are two discharges for the 130 material entering said chute. (See Fig. 34.) Motion is imparted to the box by means of a link 120^x, rock-shaft 121, and an arm 122, the latter engaging with a cam on the shaft 29,

the rock-shaft 121 being vertically mounted on a proper part of the frame A.

In order to open and close the respective branches 120 of the chute 119, there is located 5 within the latter at the base thereof a gate 124, which is pivoted to said chute and has a crank 125 connected with its axis, said crank being pivoted to a rod 126, which is operated by lever 127, operated by a cam 128, mounted 10 on a shaft journaled to the frame A, (see Figs. 34 and 34^x.) it being noticed that the gate is thrown in opposite directions, and the contents of the chute are alternately discharged through its branches. The material is now 15 to be weighed. Below the chutes 120 are two weighing apparatus M, the pans whereof are below the branches 120 of the chute 119, (see Fig. 34,) said apparatus being automatic and similar to that shown in the application for 20 Letters Patent No. 376,683, granted to me the 17th day of January, 1888. When a predetermined quantity of material enters the scale-pan, the latter is tilted and the material drops into the chute J², and is thus directed into 25 the bag.

In order to obtain accuracy in weighing, the box 113 is adjusted to weigh a quantity slightly less than that of the full weight. The box is filled and overflows, the overflow being 30 guided laterally by a spout 129 at the side of a guide-chute 130 above the box 113, the overflow thereby dropping into a cylinder or box 131, having a false bottom or rotary disk 132, to which rotary motion is imparted by means 35 of a shaft 133, a pulley 134, an endless belt or chain 135, the shaft 29, and a pulley 136 on the shaft 29, to which motion is imparted by means of bevel-gearing 137 and a driving-wheel 138, the latter being mounted on the 40 horizontal shaft N on the frame A.

Motion is imparted to the endless apron of the elevator L by means of a gear-wheel 138^x, meshing with a pinion 139, a pulley 140, an endless belt or chain 141, and pulley 142. 45 The bottom proper 143 of the box 131 has two openings 144, which register with two discharge pipes or chutes 145 146, which latter communicate, respectively, with the two pans of the weighing apparatus M. The false bottom 50 132 has two rows of perforations which are adapted to communicate with the two openings 144, respectively. (See Fig. 33.) On one side of the cylinder 131 and in the bottom 143 is an opening 147, which communicates with a pipe 148, the latter leading to the hopper K. (See Figs. 30 and 46.) As the false bottom rotates and its perforations are filled with coffee or other material, the latter remains on the bottom proper 143 until 55 said perforations reach the perforations 144, the coffee, &c., then dropping into the pipes 145 and 146, and so reaching the scale-pans M. The pans are supplied from the branches 120 with about the amount to be weighed, but 60 the few beans or grains of material from within the pipes 145 or 146 drop into the scale-pans 65

and cause the latter to receive their full weight, whereby they descend, after which they are tilted by a descending rod or lever 149, and the contents enter the feed-pipe J² 70 and so reach the bag, said rod or lever 149 being employed in other weighing apparatus for a similar purpose. The surplus beans or grains in the box 131 pass through an opening 131^x in a diaphragm or deflector 131^{xx} in said box, and so reach the opening 147 and the pipe 148, by which they are directed into the hopper K. (See Fig. 32.) A brush 132^x is within the box for each pipe 145 and 146, so as to prevent binding or clogging of the 80 material. In the scale-beams, at the centers thereof, are depending pipes 150, with which the pipes 145 and 146 are respectively in communication. Below said pipes 150 are deflectors 151 of inverted shape, one side of 85 each of which directs the scale-pans and the other to a hopper 152, which is in communication with the hopper K. Now when the pan descends the pipes 150 are directed toward the hopper 152, and the descending 90 beans or grains or material are deflected from the pans and rolling down the side of the deflector toward the hopper 152 enter the latter, the supply to the scale-pans thus being cut off. 95

The above-described measuring and weighing mechanism embodies a number of novel devices, some of which form the subject-matter of my application filed August 5, 1890, Serial No. 361,073, and others of which will 100 form the subject-matter of another or other applications for Letters Patent, and they are shown here simply to give a correct idea of the whole machine, of which the devices here claimed form a part. 105

Located in the plate J is an opening j with an attached spout 153, which is in the path of the pockets, one 95^x, as seen in Fig. 1, resting over it. Across said opening is a bridge 154, on which the bags rest while or after being filled. Now should the bottom of the bag be improperly glued or closed it will open and allow the contents of the bag to escape through the space j and enter the spout 153, by which they are directed to a box or other 110 place of collection. The rim J' now moves the distance of another tooth, and the bag, having its bottom properly closed and its contents retained, is carried over the pin or pins 155, (see Figs. 1 and 35,) said pins passing 115 through the bottom of the table J near the periphery thereof and connected with a flat spring or spring-plate 156, the latter being secured to a lever 157, which is pivoted to the frame A and carries a tooth 158, which is engaged by a ratchet-wheel 159, the teeth whereof are irregular, whereby shaking motions are imparted to the bag, while it is stationary over the pins and the contents of the latter are shaken and packed. The spring 156, 120 being quick acting, acts to quickly lower the pins just a little ahead of the descent of the 125

package. Then the latter drops on the bed or table and thus gets an additional shake. A portion of the periphery of the ratchet 159 is untoothed, as at 160, so that there is a dwell 5 in the shaking action, and the pins are lowered below the table when the pockets are in motion. The movement of the pocket which carries the bag from over the shaking-pins brings it to the position in which its top is 10 closed down and the package substantially completed. In this position the bag rests upon a plunger 198, which passes, as is shown in Fig. 37, through an opening in the bottom of the table J, the said plunger being attached 15 to levers 199 and 200 and actuated by a cam 201, secured to shaft 202. After having come to a standstill over plunger 198 the said plunger moves downward, carrying the filled bag with it, and then upward. During this upward movement of the bag-folding devices 20 substantially similar to those described in connection with the folding of the bottom of the bag are brought into action, a plate 185 moving inward to fold down the back of the 25 bag and triangular folders 184 following closely after said plate and engaging the upwardly-projecting sides of the bag. These folders commence to turn outward during the last portion of the elevation of the bag 30 on plunger 198, and when the bag has been again raised to the level of the top of table J the back flap is folded down upon the contents and the side flaps turned out. The folder-plate 185 is then withdrawn and the folder-plate 192 35 moves forward to fold down the front flap of the bag upon the contents thereof and over the back flap. This folder-plate 192 is secured to a sliding bar 194, which reciprocates in the fixed guides by means of a spring-tongue 194^x, 40 and has secured to its top friction-rolls 193. A reciprocating motion is given to the bar 194 by the cam 197 through the medium of the pivoted lever 196 and the link 195. During the inward motion of the sliding bar 194 plate 45 192 is held in a position slightly above the top of the pocket by the spring 194^x until the said plate is in position, or nearly so, upon the top of the bag, when the plunger 180 moves downward, coming in contact with the 50 rollers 193 and pressing the plate 192 down upon the top of the bag during the latter part of its inward motion.

The described method of folding down the top of the bag, by which the bag is lowered 55 and then brought gradually upward during the operation of folding down the first flaps and by which the folding-plate which turns down the front flap of the bag engages the flap at a level above the top of the pocket 60 and above the contents of the bag, is highly important, as by these devices I am enabled to fold a neat square top upon the package without having any fixed forming device within the same. The granular filling of the 65 package of course would afford an insufficient resistance to serve as a forming device, but

in connection with the peculiar movements noted the said contents do afford sufficient resistance to insure the proper folding of the top.

Before describing the remaining operations of folding the top of the bag I will here note that after the plunger 198 has accomplished its function and raised the bag to the level of the top of table J the package is firmly 75 grasped and compressed in the pocket in which it has heretofore remained in loose contact, or, rather, I should say that the movable side of the pocket moves in while and after the plunger is raising the package. This 80 is accomplished by forming the pocket in sections, (see Figs. 42 and 44,) one section 161 being movable and guided on the other section, as shown, or in any convenient way. The movable section 161 is thrust in so as to clamp 85 the bag in the pocket. As shown, this is accomplished by a sliding bar 163 moving in guides secured to the top of table J and having rollers 162 arranged to come in contact with the movable side 161 of the pocket. The 90 bar is moved inwardly at the proper time by means of a cam 166, lever 165, and link 164, and the packing is held tightly clamped during the whole operation of folding down and securing its top and then released as the series 95 of pockets resume their intermittent rotation.

To return now to the folding of the top of the bag, it is necessary to apply paste to the outwardly-turned triangular side folds, and having been pasted the angular folders 184 100 turn inward and fold the triangular side folds down upon the front and back flaps of the bottom, the folding-plate 192 being withdrawn in advance of the inward movement of the angular folding-blades. The said angular 105 folding-blades 184 are then drawn backward to their original position, and the plunger or presser-plate 180 again moves down upon the folded top of the bag, defining and pressing the pasted portions together. As shown in 110 the drawings, the plunger 180 is actuated by a cam 182 on shaft 183 by means of connecting-links 181^x and it is guided in a slide 181.

The mechanisms shown in the drawings for actuating the angular folder 184 are for giving them their reciprocating motion, the cam 187, the lever 186, and the sliding bar 185^x connected with said lever by a link, as shown. The folders lie parallel to the bar 185^x and are journaled to it by means of shafts, which 120 are provided with elongated gear-wheels, which engage a rack-bar 188, which bar is moved by a cam 191 through the medium of lever 190 and link 189. The folder-plate 185 is operated by a cam 191^{xxxx} through the 125 medium of lever 191^{xxx}, link 191^{xx}, and the sliding bar 191^x.

I will next describe the mechanism shown in the drawings for applying paste to the triangular flaps formed on the top of the bag, 130 as above described.

167 (see Figs. 36 and 37) is a paste-carrying

disk or table centrally pivoted on a sliding bar 172 and having a ratchet 168 secured to its axial pin.

169 designates a pawl, which is pivoted on an arm 170, said arm being in turn connected with the frame by means of a link 171. It will readily be seen that as the slide 172 moves in or out the action of the pawl will be to turn the ratchet and revolving paste-table 167. 170 The sliding plate 172 is given a reciprocating motion by means of the cam 175, with which it connects through link 173 and levers 174, attached to the ends of the rock-shaft 174^x; one engaging the link 173 and the other the cam 175, as shown in Fig. 36.

176 176 are pasters secured to the ends of vertical rods, which in turn are secured to the sliding rod 177, which rod is given an up and down motion by the cam 179, with which it is connected by a link 178. The pasters are arranged so as to come immediately over the outwardly-turned triangular flaps of the bag-top.

The action of these devices is as follows: 25 The paste-carrying table 167 is moved so as to come beneath the pasters 176. The said pasters are then moved downward, so as to come in contact with the table and take a supply of paste from it. They then move upward and the table is retracted or moved back out of their path, and the pasters are then again moved downward until they come in contact with the outwardly-turned flaps of the bag-top secured on the angular folding-plates 184, 30 to which flaps they impart the requisite amount of paste, and they are then moved upward out of the way when the angular folders turn inward to fold the flaps down upon the top of the bag. When the closing 35 of the top of the bag is completed, the rim J' again moves, causing the pocket 95, having the bag within the same, to pass under a steam or drying chamber 203, mounted over portions of the table J, steam being admitted 40 into said chamber, as at 204, and discharged, as at 205. The bottom of the drier is flat and it rests upon the top of the bags, it being pressed down, if desired, by springs. (See Fig. 3.) The bag, after having passed under 45 said drying-chamber, must now be removed from the pocket 95. To accomplish this I use a plunger 206, (see Fig. 39,) operated by means of a link 207, lever 208, and cam 209 are employed, said cam being secured to a 50 shaft 210, mounted on the frame A, said plunger and the bag in their raised positions being shown in dotted lines. Pivoted to a depending stem 206^x of the plunger 206 is an elbow-lever 211, which is held in elevated position by means of a spring 212. As said plunger rises, it carries with it the elbow-lever 211, the limb 213 of which enters the pocket 95. One of the rollers 214, pivoted to the other limb of the lever, strikes the under side of the 55 table J and causes said limb 213 of the lever 211 to move outwardly, as indicated by an arrow, and consequently presses against the in-

side of the movable section 161 of the pocket 95 and restores it to the open position shown in Fig. 44 prior to receiving another bag to 70 be filled, &c. When the bag is raised clear of the pocket 95, it is in position to be directed to an endless belt or apron 215, from which it is taken and stored, shipped, &c. (See Figs. 39, 40, and 41.) In order to accomplish this 75 a slide 216, guided in the frame A, with slots 217, is employed, the same being operated by a link 218, an elbow-lever 219, and a cam 220, secured to a shaft 221, mounted on the frame A. When the bag leaves the pocket 95, it is 80 in an oblique position relatively to the endless belt or apron 215. (See Fig. 40.) In order to properly place the bag on said endless belt or apron the slots 217 are partially oblique, so as to guide the slide 216 in both a 85 forward and oblique direction, as indicated by arrows in Fig. 40, and thus cause the bag to turn on the finger 222, so as to be in position shown in Fig. 41, said finger 222 being secured to a guard or a wall 223, mounted on 90 the frame A and located on the side of the endless belt or apron 215. Secured to the frame A are pins 224, which enter the slots 217 in the slide 216. As the latter is moved forward, it is, owing to the slots and pins 95 above mentioned, guided in the oblique direction, hereinbefore described.

The endless belt or apron 215 is operated by means of a pulley 225, around which said apron passes an endless chain or belt 226, a 100 pulley 227, and an endless belt or chain 228, which passes around pulleys 229 and 230, said pulleys being properly mounted on the frame A, (see Fig. 30,) the pulley 230 being connected with the pulley 142 or shaft thereof, as seen 105 at the top of said Fig. 30.

Motion is communicated to the different parts of the device by the driving-shaft D^x, Fig. 47, having a worm thereon which engages with a worm-wheel on the shaft 29, the latter 110 having the bevel gear-wheel 231, which meshes with a bevel gear-wheel 232 on the shaft B'. The bevel gear-wheel 233 on the shaft B' meshes with a bevel gear-wheel 234 on the shaft 37, imparting motion to the same. The 115 cog-wheel 235 on the shaft B' operates the conveyor.

The bevel gear-wheel 236 on the shaft 37 meshes with a gear-wheel 237 on the shaft B² and operates the latter. The bevel gear-wheel 238 on the shaft 29 meshes with a bevel gear-wheel 239 on the shaft B and imparts motion to the same. A bevel gear-wheel 240 on the shaft B meshes with a bevel gear-wheel 241 on the shaft B³, imparting motion thereto. The bevel gear-wheel 242 on the shaft B 120 meshes with the bevel gear-wheel 243 on the shaft 19 and imparts motion thereto. 125

Having now described my invention, what I claim as new, and desire to secure by Letters 130 Patent, is—

1. The combination, with a rotatable and vertically-movable shaft carrying pasters and carriers, as E, of mechanism for giving said

carriers an intermittent rotary and vertical motion, as described, an intermittently-rotating paste-table C, a blank-table 11, a table 12, arranged opposite the paste-table, and a depositing-platform, as matrix E^x, all substantially as and for the purpose specified.

2. The combination, with a rotatable and vertically-movable shaft carrying pasters and carriers, as E, of mechanism for giving said carriers an intermittent rotary and vertical motion, as described, an intermittently-rotating paste-table C, a blank-table 11, a table 12, arranged opposite the paste-table, a matrix E^x, having wings 14 arranged to receive a blank from the carrier, a paper-holder, as H, adapted to hold the blank on the matrix as the carrier arises therefrom, and mechanism arranged, as described, to turn the matrix down and move it forward to deliver its blank to the former.

3. In combination with a rotatable and longitudinally-movable shaft having pasters and carriers attached thereto, mechanism for intermittently raising and lowering said shaft, a reciprocating pin, as 45, arranged to engage the shaft, as by slotted plate 43, as it rises and to rotate it through a determined arc, and one or more locking-pins arranged, as specified, to hold the shaft against rotation when it is disengaged from the reciprocating pin, all substantially as and for the purpose specified.

4. In a machine for forming bags, the combination, with rotating mechanism, substantially as specified, for applying paste to and transporting sheets of paper, of a mold F, a movable matrix adapted to move from a substantially horizontal to a vertical position and to move to and from the mold, as described, and so that the said matrix will receive a sheet of paper in its horizontal position and then turn up and move toward the mold to fold the sheet about the same, and folders, as G G, reciprocating on the back of the mold and acting to fold the ends of the blank over the same to form a tube.

5. In a machine, substantially as specified, the combination of a mold or former F, formed of relatively adjustable sections, so as to adapt it for tubes of varying size, a matrix E^x, and reciprocating folders G, arranged and adapted, as described, to fold a blank around the former.

6. In a machine, substantially as specified, the combination of a mold or former F, formed of relatively adjustable sections, so as to adapt it for tubes of varying size, a matrix E^x, having an adjustable back plate 24^{xx}, and folders G, arranged and adapted, as described, to fold a blank around the former.

7. In a machine for forming bags, the combination, with a mold or former F, of a folder-blade adapted to move under the front end of the mold and fold in the paper overlapping the same, a pair of reciprocating and rotatable angular blades 72, adapted to engage the overlapping side edges of the tube and fold

them out and in, as described, a folder 85, adapted to fold in the back overlapping edge of the blank, and mechanism for operating said folders, as described, and so that the back-folder 85 operates after the outward and before the inward movement of the angular side-folders.

8. In a machine for forming bags, the combination, with a mold or former F and mechanism, substantially as specified, for folding and pasting a bag around the same, of a plunger 90, having an actuating-rod extending through the former and adapted to move to and from the bottom of said former, as described, and a plunger or presser-plate 96, adapted to clamp the folded bottom of the bag against plate 90 and to move down with said plate as the bag is thereby removed from the former.

9. In a machine for forming and filling bags, the combination, with a mold or former F and mechanism, substantially as specified, for folding and pasting a bag around the same, of a plunger 90, having an actuating-rod extending through the former and adapted to move to and from the bottom of said former, as described, a plunger or presser-plate 96, adapted to clamp the folded bottom of the bag against plate 90 and to move down with said plate as the bag is thereby removed from the former, and a series of rotating pockets, as 95, through which the plungers move and which carry off the bags, as described, from between said plungers.

10. In a machine for filling bags, the combination, with a bag former or mold F, having a plunger at its bottom adapted to move from and to the same, of a table J, a plunger situated beneath the former F, adapted to contact with the former plunger, as described, and to remain normally flush, or nearly so, with table J, and a series of intermittently-rotating pockets moving over the face of the table and through which the plungers move to place a bag in each pocket.

11. In a machine for filling bags, substantially as described, the intermittently-rotating series of pockets, in combination with a table J, over which said pockets move, an opening J, formed in the table in the path of the pockets, the bridge 154, crossing said opening, and a filling-chute, as J², situated over or in advance of the opening, all substantially as and for the purpose specified.

12. In a machine for filling bags, a series of intermittently-rotating pockets, each adapted to contain a bag, a table, as J, over which said pockets move and upon which the bags rest, a spout, as J², situated in the path of the pockets and adapted to fill the bags, a shaking device, as pin or pins 155, situated in the table J at a point in advance of spout J and over which the pockets rest in their intermittent rotation, and mechanism for intermittently actuating said shaker, as described, and so that it will remain out of action except when a pocket comes to rest over it.

13. In a machine for packing bags, the device for closing the end flaps thereof, consisting of tucker-blades, as 185 and 193, adapted to act on opposite sides thereof, reciprocating and reciprocally-rotating angular blades, as 184, adapted to operate, as described, to fold the side flaps of the bag end, a reciprocating paste-table moving in and out over the end of the bag, and pasters 176, situated at the 5 sides of the bag and over the folders 184 when they are turned outwardly, and mechanism for actuating said pasters, folders, and paste-table, substantially as described, and so that the pasters will alternately take up paste 10 and deposit it upon the outwardly-turned side flaps of the bag.
14. In a device for closing the end of a filled bag, the combination, with mechanism for folding down the end of the bag, substantially as described, of a pocket, as 95, adapted to hold the bag in place, a reciprocating plate or platform, as 198, for supporting the bag, and mechanism for actuating said plate, as 15 described, and so that the bag is gradually raised as the folding mechanism acts upon the upper end thereof.
15. In a device for closing the end of a filled bag, the combination, with the folding plate or tucker 185 and the reciprocating and reciprocally-rotating folders 184, of the folder-plate 192, secured to a reciprocating spring-arm 194^X, and the plunger 180, arranged as 20 described, to press said folder-plate down against the top of the bag after it has partly 25 folded the front flap down thereon.
16. In a machine for packing bags, the combination of a series of intermittently-moving pockets, a table, as J, over which said pockets move, mechanism for closing the top 30 of the bag, substantially as described, comprising a tucker-blade 185 and reciprocating and reciprocally-rotating side-folders 184, an opening in table J, situated beneath the said mechanism, a vertically-movable plate or 35 plunger 198, situated in line with said opening and movable to and below the same, and mechanism for actuating said plate, as described, and so as to lower the bag below table J as it comes upon said table and then 40 raise it again as the said folding-blades operate upon its upper end.
17. In a device for closing the ends of filled paper bags, the combination of a pocket, as 45 95, for holding the bag in place, a vertically-reciprocating plate or plunger 198, upon which the bag rests, folder 185, the side-fold- 50 ers 184, operating, as described, during the upward movement of plate 198, the folder 192, held on reciprocating spring-arm 194^X, and the plunger 180, arranged, as described, to press plate 192 down on the top of the bag, all substantially as and for the purpose specified.
18. In a device for closing the ends of filled paper bags, the combination of a pocket, as 55 95, for holding the bag in place, having a movable section, a vertically-reciprocating plate or plunger 198, upon which the bag rests, folder 185, the side-folders 184, operating, as described, during the upward movement of 60 plate 198, mechanism arranged to press in the movable section of the pocket as the plunger raises the bag to its highest position and thus compress the package, the folder 192, held on reciprocating spring-arm 194^X, and the plunger 180, arranged, as described, to press plate 192 down on the top of the bag, all substantially as and for the purpose specified.
19. In a machine for packing bags, the combination of a series of intermittently-moving pockets having a movable side, the table J, over which said pockets move, mechanism for delivering bags into the pockets and for filling 70 said bags, folding mechanism for closing the tops of the filled bags, a device for moving in the movable side of the pocket and compressing the package arranged to operate prior to the closure of the top thereof, and mechanism arranged to draw out the movable side of the 75 pocket prior to its reception of another bag, all substantially as and for the purpose specified.
20. In a machine for packing bags, the combination of the intermittently-rotating series 80 of pockets, the table J, and a drier, as 203, arranged above the path of the pockets and between which and table J the bags are carried.
21. In a machine for packing bags, the combination of the intermittently-rotating series 85 of pockets, the table J, the plunger 206, arranged, as described, to force a package from each pocket, the belt 215, the finger 222, and the slide 216, having a simultaneously-reciprocating movement longitudinally and laterally, all substantially as described, and for 90 the purpose specified.

H. E. SMYSER.
